CLAIM

The ornamental design for an eyeglass component, as shown and described.

DESCRIPTION

FIG. 1 is a front perspective view of an eyeglass component showing an embodiment of the new design;

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof; and,

FIG. 6 is a bottom plan view thereof.

The dot-dash-dot broken lines in the Figures around the lateral portion of the face of the eyeglass and in FIGS. 1, 3, 5, and 6 around a portion of the nosepiece of the eyeglass denote unclaimed boundaries of the claimed design, and the dash-dot broken lines in the Figures show portions of the eyeglass which form no part of the claimed design.
